UNITED STATES PATENT OFFICE

2,475,008

LAND MINE HOUSING

William S. Catherwood, Jr., Brooklyn, N. Y., assignor to Murray Manufacturing Corporation, Brooklyn, N. Y., a corporation of New York

Application March 30, 1944, Serial No. 528,695

4 Claims. (Cl. 102—8)

1

The invention herein disclosed relates to a land mine and more particularly to a housing which constitutes a part of a land mine and holds the detonator, propelling charge and projectile.

Heretofore and prior to this invention, the housing constituting a part of a land mine consisted of a heavy cast-iron base having two openings therethrough and containing a pocket for the propelling charge. To one of these openings a cylinder for a projectile is secured, commonly by silver solder. The other opening is tapped and one end of a thread pipe is threaded into the opening. A coupling is attached to the other end of the pipe and into this coupling the detonator is threaded. These housings are very heavy, expensive to manufacture and require considerable time and care in assembly.

An object of this invention is to provide such a housing constituting a part of a land mine in which the base is constructed from sheet metal by stamping and welding operations. Another object of the invention is to provide a construction that is considerably lighter in weight, that requires less metal, that is suitable for mass production and that is comparatively inexpensive.

The foregoing objects and certain advantages that will hereinafter appear are realized in the embodiments of the invention illustrated in the accompanying drawings and described in detail below.

The drawings include:

Fig. 1 which is a plan of a land mine housing embodying the invention;

Fig. 2 which is a sectional elevation of the same taken on the line 2—2 of Fig. 1; and

Fig. 3 which is a sectional elevation of a slightly modified form of land mine housing.

The housing which forms a part of a land mine, that is illustrated in Figs. 1 and 2 of the drawings essentially consists of a hollow base 1 having openings 2 and 3 through one end wall thereof, a cylinder 4 united to the base coaxially with the opening 2 of larger diameter and a tube 5 united to the base coaxially with the opening 3 of lesser diameter. The base contains the propelling charge for propelling a projectile, such as a mortar shell that is received in the cylinder 4. The tube 5 supports the detonator.

In the housing illustrated the base 1 consists of two similar horizontally divided sections 6 and 7 stamped from heavy sheet metal. The openings 2 and 3 are punched through the end wall 8 of the upper section 6. At the opening 3 the metal of the end wall is extruded to form an axially extending flange 9. To the end edge of

2

the flange 9, one edge of the tube 5 is butt welded, preferably by the electric resistance method of welding. The other end of the tube is threaded internally as at 10 to receive the detonator. With this arrangement no coupling is required to secure the detonator to the tube.

The cylinder 4, is of larger diameter than the opening 2. It is provided with an inturned flange 11 having an axial extension 12. The axial extension is received in the opening 2 and is spun over to form an outwardly extending section 13 embracing the metal of the wall 8 surrounding the opening 2 and securing the cylinder to the base. In this way the cylinder is secured to the base and a tight connection between the cylinder and the base is secured.

The cylinder, and preferably the tube 5, are secured, as above described, to the upper section 6 of the base before the sections 6 and 7 are united. These sections of the base are united in edge to edge relation by butt welding the edges as at 14. Preferably, the welding of the sections of the base is effected by the electric resistance welding method. In this way, the sections are integrally united and the method is suitable to mass production.

The shape of the base is as illustrated in Fig. 1 of the drawings. With this shape, the base is sufficient and of a size such as to hold the land mine with the cylinder 4 and tube 5 vertical, the position in which such land mines are usually placed.

The land mine housing illustrated in Fig. 3 is similar to the one above described except for the manner in which the cylinder 15 is united to the upper end wall 16 of the base 17. In this construction, the cylinder is welded, by electric resistance welding, to the base. Thus, all parts are assembled and integrally united by the method of electric resistance welding.

In the construction illustrated in Fig. 3, the metal at the opening 18, at which the cylinder 15 is united, is extruded to form an axially extending flange 19 surrounding the opening. The end of the cylinder 15 united to the base has an in-turned flange 20 having a hook shaped end to provide an axial extension 21. The extension 21 abuts the flange 19 and is butt welded thereto. When the weld is completed, the base 22 of the cylinder engages the end wall 16. Any burr extruded during the weld is confined between the flange 19 and the base 22 of the cylinder.

From the foregoing description of the illustrated embodiments of the invention, it will be apparent to those skilled in the art that by the in-

vention there is provided a land mine housing that is constructed from sheet metal by stamping and forming operations, that is assembled by like operations and welding operations and that is comparatively light in weight, readily manufactured by mass production methods and comparatively less-expensive.

It will be obvious that various changes may be made by those skilled in the art in the details of the embodiments of the invention illustrated in the drawings and described in detail above within the principle and scope of the invention as expressed in the appended claims.

I claim:

1. A housing constituting a part of a land mine comprising a hollow base for containing the propelling charge, a cylinder for containing a projectile and a tube connected to the base for containing the detonator, the base consisting of two horizontally divided sections struck up from sheet metal and welded at their contacting edges, one of said sections having two openings therethrough and the cylinder being united to the base at one of said openings and the tube united to the base at the other of said openings.

2. A housing constituting a part of a land mine comprising a hollow base consisting of two horizontally divided sections united in edge to edge relation, one of said sections having two openings of different diameters through the wall thereof, a cylinder of greater diameter than the larger opening for containing a projectile, the cylinder having an inturned flange and united to the base coaxial with the larger opening, and a tube welded at one end to the base coaxial with the opening of lesser diameter.

3. A housing constituting a part of a land mine comprising a hollow base consisting of two horizontally divided sections united in edge to edge relation, one of said sections having two openings.

5 of different diameters through the wall thereof, a cylinder of greater diameter than the larger opening for containing a projectile, the cylinder having an inturned flange spun about the edge of the opening of larger diameter, and a tube welded at one end to the base coaxial with the opening of lesser diameter.

4. A housing constituting a part of a land mine comprising a hollow base consisting of two horizontally divided sections united in edge to edge relation, one of said sections having two openings of different diameters through the wall thereof and an axial flange surrounding each opening, a cylinder of greater diameter than the opening of larger diameter for containing a projectile, the cylinder having an inturned flange with an axial extension united in edge to edge relation with the axial flange surrounding the opening of larger diameter, and a tube united in edge to edge relation with the axial flange surrounding the opening of lesser diameter.
